Term of patent 14 years

Int. Cl. D2—03

U.S. Cl. D2—234

FIG. 1

FIG. 2

FIG. 3

FIG. 4

FIG. 1 is a top perspective view of sport goggles showing my new design;

FIG. 2 is a bottom perspective view thereof;

FIG. 3 is a front elevational view thereof;

FIG. 4 is a side elevational view of the sport goggles. The side not shown has substantially the same appearance as the side shown.

The shading is partially shown on the strap for convenience of illustrating, it being understood that the shading is uniformly continuous along the length of the strap.

I claim:

The ornamental design for sport goggles, substantially as shown and described.
